(57) **CLAIM**

The ornamental design for a mobile robot for object detection, as shown and described.

DESCRIPTION

FIG. 1 is a front-left perspective view of a mobile robot for object detection;

FIG. 2 is a rear-left perspective view of the mobile robot for object detection;

FIG. 3 is a rear-right perspective view of the mobile robot for object detection;

FIG. 4 is a front side view of the mobile robot for object detection;

FIG. 5 is a left side view of the mobile robot for object detection;

FIG. 6 is a rear side view of the mobile robot for object detection;

FIG. 7 is right side view of the mobile robot for object detection;

FIG. 8 is a top view of the mobile robot for object detection; and,

FIG. 9 is a bottom view of the mobile robot for object detection.

In the drawings, the dash-dot broken lines define a boundary of the mobile robot that forms no part of the claimed design. The dashed broken lines depict portions of the mobile robot that form no part of the claimed design. The relatively light shade lines on the surface portions indicate contour not surface decoration.
